UNITED STATES PATENT OFFICE.

HENRY E. REEVE, OF NEW YORK, N. Y.

ELECTRICAL APPARATUS.

1,109,940.

Specification of Letters Patent.

Patented Sept. 8, 1914.

Application filed February 17, 1911. Serial No. 609,193.

To all whom it may concern:

Be it known that I, HENRY E. REEVE, a citizen of the United States, and resident of New York, in the county of Kings and State of New York, have invented certain new and useful Improvements in Electrical Apparatus, of which the following is a specification.

My invention relates particularly to a construction for affording a gas and liquid tight connection between a casing and a lever for transmitting motion through a wall of the casing, as for instance, in the electric operating mechanism of my former applications. In the said applications I have shown and described in detail a construction in which the hermetically sealed casing contains the parts to be protected and the liquid and gas tight connection is effected by means of a suitable metallic diaphragm through which the transmitting lever extends. One of the plates of this diaphragm is connected to the transmitting lever and the other to a wall of the casing having an opening through which the transmitting lever passes. I have found that the useful life of this diaphragm construction may be prolonged very greatly by a construction shown and described in detail hereinafter. These improvements consist in the employment of certain special bushings, flexible washers and collars whereby the strain of flexure of the diaphragm is so distributed throughout the diaphragm as to greatly reduce any tendency to fracture from prolonged or repeated vibrations.

Figure 1, is a front view of an electrical bell construction embodying the improvements of my invention, the front plate or cover of the casing being removed. Fig. 2, is an enlarged cross sectional view of the diaphragm embodying the improvements of the present invention. Fig. 3, is a plan view of the diaphragm with the collar, bushing and transmitting lever in section. Fig. 4, is a dropped perspective view showing the parts of the diaphragm and the parts for connecting it to the casing and transmitting lever.

The casing 1 of any suitable shape and character, incloses such parts as it is desired to protect, for instance, the electromagnet 2, the armature 3 and the vibrator contacts 4 and 5 which are operated in a suitable manner by the electromagnet.

The bell or gong top 6 is mounted outside the casing and is struck by means of a ham-

mer or striker 7. The lever 8 passing through an opening in one wall of the casing is connected at its inner end to the armature 3 and its outer end to the striker 7. The water and gas tight connection between the transmitting lever and the casing is effected by means of the diaphragm 9. While the diaphragm 9 is capable of supporting the transmitting lever and the attached parts I prefer to provide additional guiding and supporting means as for instance, the pivots 10 which constrain the diaphragm and lever 8 to vibrations in a single plane. This diaphragm is formed of thin metal plates 14 and 15 preferably of oval outline as shown in Fig. 3 united by a tight joint at their periphery. The upper plate 14 is secured to the bushing 16 to which the lever 8 is secured. The inner end of the bushing 16 has a flange 17. Between the flange 17 and the plate 14 I have arranged a flexible metal washer 18. A similar flexible metal washer 19 is mounted above the plate 14. The collar 20 fits on the bushing 16 above the washer 19 and the parts are drawn and held together in a suitable manner, for instance, by turning over the outer upper edge of the bushing 16 as at 21. The metal plate 15 is secured to the casing 1 in a similar manner. A hollow bushing 22 through which the lever 8 passes freely has a flange 23. The flexible metal washer 24 is located between the flange 23 and the plate 15. A similar flexible washer 25 is arranged below the plate 15 and the parts are clamped together by means of a collar 26 which fits on the bushing 22 being drawn and held together for instance, by turning over the lower outer rim of the bushing 22 as at 27. I prefer to coat the lower and upper surfaces respectively of the washers 19 and 18 by suitable paint or enamel so as to afford a better connection and insure a tighter joint. Similarly the lower and upper surfaces of the washers 24 and 25 are preferably coated. I have found that by means of this bushing and washer and collar the strains due to repeated vibrations of the transmitting lever and the diaphragm are so distributed as to avoid fracture and increase the life of the diaphragm many times.

The plates 14 and 15 and the washers 18, 19, 24, 25 may be made for instance, of phosphor-bronze which has great elasticity and is practically non-corrosive. The other parts may be made of such material as is suitable

for the particular purposes to which the apparatus is intended.

For convenience I have used the term "bushing" in referring to the number 16 5 but it should be understood that the method of attaching the lever 8 to it is immaterial as is also the distance which the lever extends into it. It may even be closed on the upper end as shown in Fig. 4.

10. What I claim is:

1. In a device of the character described, a diaphragm consisting of two flexible plates connected at their peripheries, flanged bushings passing through said plates and having their flanges between said plates, flexible washers on said bushings between said flanges and said plates, flexible washers on said bushings outside of said plates and collars clamping the plates between the flexible washers against the flanges of the bushings, said washers extending substantially beyond the edges of the flanges and collars respectively and a transmitting lever secured to one bushing and passing through the other bushing.

2. In a construction of the character described, a bushing, a transmitting lever passing therethrough, a flexible metallic plate, a flange on said bushing, flexible washers arranged on opposite sides of the plate and a collar on said bushing for clamping said flexible washers and plate against said flange, said washers extending a substantial distance beyond said flange and collar respectively.

3. A construction of the character described comprising a casing having an opening, a transmitting lever passing through said opening in said casing, a flexible metal plate means for connecting its periphery to said casing and means for connecting the central portion of said plate to said transmitting lever, said means including flexible washers on both sides of said plate and means for clamping said washers and plate, said washers extending outward a substantial distance beyond the clamping means.

4. In apparatus of the character de-

scribed, a flexible phosphor-bronze diaphragm, and a member connected thereto 50 by a water and gas tight joint including spring phosphor-bronze washers on opposite sides of the diaphragm.

5. The combination with a casing and a vibrating lever passing therethrough, of a 55 flexible connection between the lever and casing comprising, a thin flexible metallic diaphragm, means for connecting its peripheral portion with the casing, rigid means carried by the lever and gripping 60 opposite faces of the diaphragm and thin, flexible metallic washers lying flat against the opposite faces of the diaphragm and interposed between the said rigid clamping means and the respective faces of the diaphragm, said flexible washers extending substantially beyond the rigid clamping means to elastically support the diaphragm and thereby upon vibration of the lever to reduce the deflection of the diaphragm from 70 the plane of the rigid clamping means.

6. The combination with a casing and a vibrating lever passing therethrough, of a flexible connection between the lever and casing comprising, an elastic metallic diaphragm of oval shape arranged to vibrate about a line corresponding to the shorter axis of the oval, means for connecting the periphery of said diaphragm with the casing, spring metal washers of oval shape applied to the opposite faces of the diaphragm with the axes of such washers alined with the corresponding axes of the diaphragm and rigid clamping means carried by the lever securing the spring washers in flat engagement with the faces of the diaphragm, the said washers projecting beyond the rigid clamping means to thereby reduce the degree of deflection of the diaphragm from the plane of the rigid clamping means when 90 the lever is vibrated.

HENRY E. REEVE.
